CONTROL DEVICE FOR STRAND FEED

Karl H. Andren, Greenfield, Wis., assignor, by mesne assignments, to Western Electric Company, Incorporated, New York, N. Y., a corporation of New York

Application April 19, 1951, Serial No. 221,912

7 Claims. (Cl. 242—37)

This invention relates to a wire feed control device and more particularly to a control device actuated in response to a kink or knot in the wire or in response to the depletion of the supply of wire to stop the feed of the wire.

It is an object of the present invention to provide a simple control device for use with a wire feeding mechanism for stopping the feed of the wire in response to the presence of a knot or kink in the wire.

It is the further object of the present invention to provide a control device for use with a wire feeding mechanism for stopping feed of the wire in response to the depletion of the supply of wire.

In accordance with one embodiment of the invention as applied to a wire feeding mechanism, there is provided a movable trip member having an aperture therein for freely passing only a straight wire therethrough and having a cam recess therein for receiving an arm of a switch connected to a control circuit of the drive mechanism for advancing the wire. The arm of the switch is biased into the recess of the member to yieldably maintain the member in its normal position and is moved outwardly by movement of the member by a knot or kink in the wire to actuate the switch and stop the feed of the wire. A guide member mounted for movement into engagement with the trip member is yieldably held in a normal position in spaced relation to said trip member and serves to change the direction of movement of the wire from the supply of wire on a reel to which the end of the wire is secured. When the supply of wire on the reel has been used up, the pull of the wire against the end secured to the reel will cause the guide member to move into and actuate the trip member to open the switch and stop the wire feed.

Other objects and advantages of the invention will become apparent by reference to the following detailed description thereof and the accompanying drawings illustrating a preferred embodiment of the invention, in which

Fig. 1 is a diagrammatic view of the wire feed control mechanism;

Fig. 2 is a vertical longitudinal sectional view through the wire feed control device and a reel for holding a supply of wire and showing the feed control device in its normal position;

Fig. 3 is an enlarged sectional view of a portion of the feed control device shown in Fig. 2 and with parts thereof shown in changed position; and

Fig. 4 is a front elevational view of the feed control device.

Referring to the drawings, there is shown a supply reel 10, on which is wound a supply of wire 11, one end 12 of which is secured to the reel, as by passing it through an aperture 13 in the reel, and having a knot formed on the end thereof. The reel 10 is supported on a tubular support or reel holder 15 secured to a stationary frame member 16, which forms a part of a suitable framework for supporting the control device. The head 18 of a

2

tubular clamping member 19, which is telescopically mounted within the support 15 and secured to the frame by a thumb screw 20, engages and clamps the reel against movement on the reel holder 15. The wire 11, as it is withdrawn from the supply, is guided about the reel by a tubular guide or flier 25 supported by brackets 26-26 on a rod 27 rotatably supported in the tubular member 19. The rod 27 is yieldably retained in the member 19 by a spring 28 disposed between shoulders formed on the member 19 and the rod 27.

The end 30 of the guide 25 is positioned substantially on the axis of the reel 10 and guides the wire for movement outwardly from the reel on the axis thereof into engagement with a guide roller 31 rotatably mounted for rotation on a pin 32, which is fixed to a movable U-shaped member or slide 34, and serves to rotatably support the guide roller 31 for movement with the slide. The member 34 is slidably mounted in guideways 36 formed in a pair of spaced members 37 of a guide member 38, which is secured to and supported from a plate 39. The plate 39, in turn, is attached to an angle iron frame member 40, which is connected to and supported by the frame member 16 in a suitable manner. A spring 45 secured to the slide 34 and the lower end of the guide member 38 tends to pull the carrier 34 and the guide roller 31 downwardly to their normal position, shown in Figs. 2 and 4, where the slide 34 engages an abutment in the lower portion of the guideways 36. The wire 11 passes around the guide roller 31 and is directed through an aperture 47 in a trip member 48 and into engagement with a suitable means for feeding or advancing the wire, which, as illustrated in Fig. 1, comprises a pair of feed rollers 52.

The trip member 48, which has a cylindrical contour, is mounted for vertical movement in a bore 54 of a boss or bracket 55 formed on a housing member 56, which is secured to the frame member 40 and supported in fixed position thereby. A shoulder or flange 57 formed on the upper end of the trip member 48 engages the upper edge 40 of the bracket 55 to support the trip member 48 in a normal position, indicated in Fig. 2. An annular groove or recess 58 forming cam surfaces on the trip member 48, is adapted to receive a roller 59 mounted on the arm 60 of a switch 62, which is supported by and within the housing 56. The arm 60 is tensioned for movement into the cam recess 58 and serves to yieldably hold the trip member 48 in its normal position. The bore 47 of the trip member 48 is of a size which will freely pass straight portions of the wire 10 therethrough, but which will engage and restrain the movement of a deformed portion of the wire, as, for example, a portion of the wire having a kink or a knot therein. Thus, in the event a kink or knot is formed in the wire and engages the trip member 48 as the wire is being fed, it will impart movement to the trip member which, in turn, will cam the arm 60 outwardly and actuate the switch 62 to effect the stopping of the wire feed.

One of the feed rolls 52 (Fig. 1) is connected to and rotated by an electric motor 65 connected through suitable conductors 66 and a set of contacts 67 to power lines 68 and 69. The contacts 67 are actuated by a relay 70, which is connected by a suitable conductor in series with the switch 62 and the secondary 73 of a transformer 74, the primary 75 of which is connected to the power lines 68 and 69. The parts are arranged so that with the trip member 48 in its normal position, the switch 62 is closed and the circuit from the powerline to the motor 65 is completed to cause the feeding of the wire 11. If a kink or knot is formed in the wire as it reaches the trip member 48, its passage therethrough will be obstructed and the knot will engage and move the trip member 48

and cause it to actuate the switch 62 to open position and render the wire feed inoperative.

A member 77 secured to the upper portion of the carrier member 34 has an upwardly extending narrow finger 78 disposed in alignment with the trip member 48 and with the end portion thereof spaced a predetermined distance from the member 48. In response to upward movement of the guide roller 31, the finger 78 is caused to engage the trip member 48 and move it upwardly to actuate the switch 62 and effect the stopping of the wire drive.

When the supply of wire 11 has been exhausted, the wire will be drawn taut from the end portion 12 thereof, which is secured to the reel, and the wire, as it passes from the end 30 of the tubular guide 25, will move the roller 31, the slide 34 and the finger 78 upwardly therewith to cause the finger 78 to engage and move the trip member 48, thereby actuating the switch 62 to stop the wire feed. Thus, with the above-described construction of control mechanism, the wire feed is rendered inoperative stopping the feeding of the wire in the event a kink or knot is formed in the wire or in response to the depletion of the supply of wire. In either case, the member 48 is moved upwardly to actuate the switch 62 and render the feeding device inoperative. The switch 62 manually remains open until the member 48 is reset to its normal position after the condition causing its upward movement has been remedied.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A device of the type described comprising feed means for advancing a strand including a switch disposed adjacent the path of travel of said strand for rendering said feed means inoperative in response to actuation of said switch, means for supporting a supply of strand with one end thereof secured against feeding movement, a trip member having an aperture therein for guiding therethrough a strand free of knots and for preventing the passage of a portion of the strand having a knot therein, means for supporting said trip member adjacent said switch for movement with said strand by a knot therein to actuate said switch, guide means engageable with said strand from said supply for changing the path of movement thereof from one direction to another direction and into the aperture in said trip member, means mounting said guide means for movement into engagement with said trip member to actuate said member, and means yieldably retaining said guide means in a normal position in spaced relation and adjacent to said trip member.

2. A feed control device for use with a wire feeding mechanism having a control circuit comprising a trip member having an aperture therein for receiving a wire as it is being advanced by said feeding mechanism, said aperture being of a size to freely pass a straight wire therethrough but to restrain a wire having a kink or knot therein, means supporting said trip member in a normal position and for movement with said wire, a cam on said member, an element stressed for movement against said cam for yieldably retaining said member in said normal position and movable outwardly by the movement of said trip member from said normal position by a knot in said wire, a switch connected to the control circuit of said wire feeding mechanism for rendering the wire feeding mechanism inoperative in response to the outward movement of said element, means for supporting a supply of wire with the end of the wire secured against feeding movement, guide means for receiving said wire from said supply in one direction and guiding said wire in a predetermined path in another direction, means guiding said

guide means for movement along said predetermined path from a first position into engagement with said trip member, and means yieldably retaining said guide means in said first position, said guide means being movable to actuate said trip member in response to the movement of the wire when the wire has reached the end of its supply for rendering said feed mechanism inoperative.

3. A feed control device for use with a strand feeding mechanism having a switch disposed adjacent the path of travel of said strand and actuatable to render the feeding mechanism inoperative comprising a bushing having an aperture for passing a strand free of knots therethrough and for preventing the passage of a portion of the strand having a knot therein, means for supporting the bushing adjacent the switch and for movement with said strand by a knot in the strand, a cam surface on said bushing engageable with said switch for actuating said switch in response to movement of said bushing, means for supporting a supply of strand with one end thereof secured against feeding movement, a guide roller engageable with the strand from said supply for changing the path of movement thereof from one direction to another, a carrier for rotatably supporting said roller and having a portion thereof engageable with said bushing, and means yieldably supporting said carrier in a normal position with said portion in spaced relation to said bushing and for movement with said strand to move said bushing in response to the exhaustion of the supply of strand.

4. A feed control device comprising feed means for withdrawing a strand from a supply thereof, means including an element disposed adjacent the path of travel of said strand for rendering said feed means inoperative in response to movement of said element, means stationarily mounted in relation to said feed means for supporting a supply of strand with one end thereof secured against feeding movement, guide means engageable with said strand as it is being withdrawn from said supply in a first direction for changing the path of movement thereof from said first direction to a second direction disposed transversely of said first direction, means mounting said guide means for movement toward said element, said guide means being moved into engagement with said element by said strand to actuate said element in response to the exhaustion of the supply of strand and the shortening of the strand between said feed means and said one end of said strand, and means yieldably retaining said guide means in a normal position in spaced relation and adjacent to said element.

5. In a strand feeding device, the combination of stationary means for supporting a reel of strand, feed means for withdrawing said strand from said reel, guide means having a first position engageable with the strand at a point thereon intermediate said reel and said feed means for guiding the strand from the reel to the feed means through a path greater in length than that from the reel directly to said feed means and for maintaining a substantially constant predetermined length of strand between said feed means and said reel as the strand is being withdrawn therefrom, means mounting said guide means for movement from said first position to a second position in response to the shortening of said predetermined length of strand between said reel and said feed means, resilient means for yieldably maintaining said guide means in said first position, and means operable in response to movement of said guide means to said second position for rendering said feed means inoperative.

6. In a strand feeding device, the combination of stationary means for supporting a supply of strand with one end secured against feeding movement, feed means for withdrawing said strand from said supply, guide means having a normal first position engageable with the strand at a point thereon intermediate said supply and said feed means for guiding the strand from the supply to the feed means through a path greater in length than that from the supply directly to said feed means and for maintain-

ing a substantially constant predetermined length of strand between said supply and said feed means as said strand is being fed, means mounting said guide means for movement in a predetermined path from said first position in response to the exhaustion of said supply of strand and the shortening of said predetermined length of strand between said supply and said feed means, resilient means for moving said guide means to and yieldably maintaining it in said first position, and means including an element mounted in the path of said guide means and actuatable thereby in response to movement of said guide means from said first position for rendering said feed means inoperable.

7. In a strand feeding device the combination of means for supporting a supply of strand with one end thereof secured against feeding movement, feed means for withdrawing the strand from said supply, guide means engageable with said strand at a point intermediate the supply and the feed means for changing the direction of movement thereof between the supply and the feed means and for maintaining a substantially constant predetermined length of strand therebetween, means mounting said guide means for movement in a predetermined path from

a normal position in response to the shortening of said predetermined length of strand between said supply and said feed means, resilient means for yieldably maintaining said guide means in said normal position, and means including an element disposed in the path of said guide and actuatable thereby in response to the shortening of said predetermined length of strand for rendering said feed means inoperable.
